FREDERIC H. MILLER, OF WILKINSBURG, PENNSYLVANIA, ASSIGNOR TO WESTINGHOUSE ELECTRIC & MANUFACTURING COMPANY, A CORPORATION OF PENNSYLVANIA

SUSPENSION CLAMP

Application filed December 9, 1927. Serial No. 238,795.

My invention relates to suspension clamps and particularly to clamps for suspending high-voltage transmission-line conductors.

One object of my invention is to provide a clamp of the above-indicated character that shall comprise substantially rigid clamping means to effect binding clamping of a conductor, by substantially only the inherent yieldability of the conductor and clamp parts, and that shall operate to expel the clamping members from each other, when released, in response to predetermined movement of the conductor.

Another object of my invention is to provide a suspension clamp that shall embody a novel suspending-yoke and clamping-member structure whereby fixed legs of the yoke, of less distance apart than portions on the clamping member with which they are to cooperate, may be freely passed into suspending position, during the assembly of the parts.

Another object of my invention is to provide a suspension clamp that shall be simple and durable in construction, economical to manufacture and effective in its operation.

While certain features of my invention are applicable to a suspension clamp having clamping means of any suitable type, it has these, and other, features which are particularly related to a clamp of the so-called slip, or automatic-release, type which releases the conductor, when the latter is broken, or, when, by other abnormal conditions, the suspension insulator, to which the clamp is attached, swings through a predetermined angle to one side of the normal suspended position thereof.

The part of my invention which is applicable to clamps in general, irrespective of the particular clamping means employed, although particularly adapted for the above-mentioned slip clamps, comprises a structure wherein a suspension yoke is preferably pivoted to the clamp about an axis transverse

to the conductor and substantially through the conductor axis. This feature permits normal line oscillations to move through the clamp without imposing undue vibrational stress on the suspension yoke, suspension-insulator string and adjacent tower parts, and a clamp embodying it is known as a center-trunnion clamp.

In clamps of this type, some difficulty has been experienced in providing effective pivot means, or trunnions, for attachment to a suspension element or yoke therefor, the trunnions having been mounted in position by a link-and-bolt structure which, in effect, constitute a second yoke having its free ends connected to the free ends of the suspension yoke and embracing the lower portion of the clamp. This feature adds expense and weight to the structure.

Also, in clamps of the above-mentioned slip type, many expedients have been suggested, including springs and cams of various kinds. These clamps have also embodied cam-clamping means having substantially constantly movable rubbing frictional engagement with one of the clamping members.

It has been suggested to employ cam clamping means which does not impose constant frictional wear on any of the parts but, in any of the clamps of this type of which I am aware, springs of one kind or another, have been considered essential elements.

It is my aim to overcome all of the objections above mentioned and, accordingly, in practicing my invention, I provide a clamp in which the above-mentioned second yoke and the springs of the clamps of the slip type are omitted and other structure so provided in their stead as to produce a clamp of materially improved character, economy of construction and facility of assembly.

Figure 1 of the accompanying drawings, is a side view, partially in elevation and partially in section, of a clamp constructed in accordance with my invention.

Fig. 2 is a view, taken at right angles to Fig. 1, substantially along the vertical central axis thereof,

Fig. 3 is a detail side elevational view, taken at right angles to the lower portion of Fig. 2,

Fig. 4 is a detail view, similar to Fig. 3, of a modified form of my invention, and

Fig. 5 is a central view of the modification shown in Fig. 4, taken at right angles thereto.

Referring to Figs. 1, 2 and 3, the device comprises, in general, a lower channel or clamping member 2 for the reception of a conductor 3, an upper clamping or shoe member 4, a clamping cam element 5 and a suspension member or yoke 6.

The channel member 2 is provided with flared end portions 8, a slightly depressed central clamping surface portion 9, longitudinally extending re-inforcing under-ribs 10, and laterally apertured projections 11 extending upwardly from adjacent to the centers of the side walls 14 of the channel member 2.

The upper clamping member or shoe 4 is provided with flared end portions 16, an under-surface 17 substantially conforming to the surface of the conductor 3, a slightly depending central portion 19 disposed over, and substantially conforming to, the depressed portion 9 on the channel member 2, and upwardly projecting portions 20 between the projections 11 of the channel member 2.

The cam element 5 comprises a laterally apertured central boss portion 22, a depending cam portion 23 for engagement with the shoe member 4, and upwardly projecting and diverging lug portions 24. A bolt or pin member 25 extends across the channel member 2 above the conductor 3 and through the boss portion 22 and the projections 11 which it fits relatively closely. The pin 25 also extends through vertically elongated slots 27 in the projections 20 of the shoe member 4, to permit clamping and releasing movements, and to prevent the separation of the shoe 4 relative to the channel member 2.

The yoke member 6 comprises a socket, or other suitable, portion 29, at its upper or closed end, for mounting the clamp at the lower end of a usual series-string, suspension-insulator unit or other support, and has side legs 30 disposed at opposite sides of the channel member 2. The latter is provided with trunnion portions 32 that may be provided thereon in any suitable manner and preferably are disposed in alignment with each other along an axis extending through the conductor 3.

In the above-described structure, the lower or free ends 34 of the side legs 30 of the yoke 6 are fixed in position relative to each other a less distance apart than the outer extremities of the trunnions 32 with which they are adapted to cooperate.

In order to permit the assembly of the yoke structure 6 relative to the trunnions 32, without having the trunnions 32 constitute separate members, the free ends 34 are bifurcated, as more clearly shown in Fig. 3, to permit the longitudinal passage thereof, during assembly, over the trunnions, the free ends 34 having lower portions 35 of slightly greater distance apart than the diameter of the trunnions 32. The ends 34 also have apertured central portions 36 of greater internal diameter than the opening between the lower portions 35 to receive bearing members 37 between the free ends 34 and the trunnions 32 and to provide shoulders 38 by which the trunnions 32, the free ends 34 and the bearing members 37 are interlocked in position. Cotter pins, or other yieldable pin elements 40 may be disposed in apertures in the lower portions 35 and the lower portion of the bearing member 37 to secure these members in position, as by bending over the ends of the pin 40.

In assembling the parts, above described, after the conductor 3 has been placed in the channel member 2 and the shoe member 4 and the cam element 5 placed in the positions shown, the pin member 25 is placed in position in which it is held by a cotter pin 41. With these parts so assembled, the cam element 5 may be moved to the clamping position shown by any suitable implement adapted for this purpose or it may be turned to clamping position by the yoke 6, as will hereinafter appear.

With the channel member 2, the shoe member 4 and the cam 5 assembled and clamped as above described, the lugs 24 are centrally disposed as shown and the yoke 6 may be directly placed in position, as above described, for the reception of the bearing members 37 and the pins 40.

If, however, it is desired to utilize the yoke 6 for moving the cam 5 to its clamping position, the yoke is placed in position relative to the trunnions 32 at an angle to the conductor 3 corresponding to the angle at which the cam 5 is then resting in its unclamped position. In this relation of parts, after the bearing members 37 and the pins 40 have been inserted in position, the yoke 6 may be moved to its normal operating central position, as illustrated, during which movement of the yoke a centrally depending projection 43 thereon engages one of the lugs 24 to move the cam 5 to its clamping position.

In operation, the yoke 6, in response to normal line oscillations, pivots about the trunnions 32 to permit the projection 32 to oscillate between the lugs 24, whereby the clamping action between the members 2 and 4 is unaffected. If, however, through breakage of the conductor 3, or other abnormal condition, the yoke 6 tends to move a greater distance about the trunnions 32 than is permitted

by the lugs 24, the lug 43 engages one of the lugs 24 to release the cam 5 from the shoe member 4, and, consequently, to release the conductor.

5 In the modification of my invention shown in Figs. 4 and 5, in which corresponding parts are designated by corresponding reference characters, the bearing members 37 are placed on the trunnions 32 before the passing of the 10 yoke legs thereover. The bearing members 37, instead of interlocking with the free ends 34, by means of the shoulders 38, as in the above-described figures, are interlocked with the ends 34 by means of a pin 45 which functions similarly to the pin 40 to secure the parts to each other but which also sustains the load of the clamping parts on the yoke member. In this form also, the free ends 34 are provided with outer wall portions 46 which 15 close the bearing members 37 and the ends of the trunnions 32.

While I have shown and described particular forms of my invention, changes may be effected therein without departing from the 20 spirit and scope thereof, as set forth in the appended claims.

I claim as my invention:—

1. A suspension clamp comprising a conductor-clamping member including suspension 30 portions permanently associated therewith at opposite sides thereof, a suspension yoke having free-end portions permanently related to each other a less distance apart than the outer extremities of said suspension 35 portions and adapted to pass into suspending relation to said suspension portions during the assembly of said clamping member and yoke, and members for placement between said suspension and free-end portions and 40 constituting bearing and interlocking means therefor.

2. A suspension clamp comprising a conductor-clamping member including suspension 45 portions permanently associated therewith at opposite sides thereof, a suspension yoke having free-end portions permanently related to each other a less distance apart than the outer extremities of said suspension 50 portions and adapted to pass into suspending relation to said suspension portions during the assembly of said clamping member and yoke, bearing means adapted to be placed between said suspension and free-end portions, and means for securing said bearing 55 means in position.

3. In combination, in a cable-suspension clamp, a cable-receiving member, a cooperating relatively movable clamping member, a member pivotally connected to said receiving 60 member for actuating said cooperating member to clamping position, and means for permanently connecting said cooperating clamping member in lost-motion interlocking relation to said receiving member.

65 4. In combination, in a cable-suspension

clamp, rigid cooperating cable-clamping members, a rigid member for actuating said members to clamping position, said members operating substantially only by reason of inherent yieldability thereof and of the conductor to effect binding clamping of the conductor, and a clamp suspension member pivotally connected to one of said clamping members and adapted to engage said actuating member to release said clamping members only when the pivotal movement between the suspension member and the member to which it is pivoted exceeds a predetermined angle.

5. In combination, in a cable-suspension clamp, a cable-receiving channel member having registering pin-receiving portions associated with its opposite side walls, a pin supported by said portions and extending across the channel, a cooperating clamping member in the channel having a pair of slotted side portions interlocking said pin in lost-motion relation thereto, a member mounted on the pin between said side portions for actuating said cooperating clamping member to clamping position, and a suspension member pivotally connected to the channel member, one of said actuating and suspension members having a pair of projections and the other a projection disposed between the pair in spaced relation thereto whereby the actuating member is normally prevented from release except in response to predetermined movement between the channel and suspension members.

6. In combination, in a cable-suspension clamp, a cable-receiving channeled clamping member including pivot-support portions above the cable-receiving position for a clamping-action-effecting member and pivot-support portions oppositely disposed on the outer sides of the channel member below said first pivot-support portions for a suspension yoke, a cooperating clamping member for position above the conductor position in the channel below said first pivot-support portions, a clamping-action-effecting member pivotally supported by said first pivot-support portions and adapted to transmit its clamping forces from said channel member to said cooperating clamping member entirely through substantially rigid parts, and a clamp-suspension yoke pivotally supported by said second pivot-support portions, one of said clamping-action-effecting and suspension-yoke members including a pair of spaced portions and the other a portion between said spaced portions normally in spaced relation thereto to permit predetermined pivotal movement between the yoke and the channel member and to cause the yoke to engage the actuating member when the pivotal movement exceeds said predetermined movement in either direction.

7. In combination, a cable-suspension clamp including co-operating cable-clamping members and means for actuating said mem-

bers to clamp and release the cable, said members and means operating independently of positive spring-actuating effect to clamp and release the cable, and a clamp suspension member pivotally connected to the clamp and adapted to operate said actuating means to release said clamping members relative to each other only when the pivotal movement between the suspension member and the clamp exceeds a predetermined angle.

10 In testimony whereof, I have hereunto subscribed my name this 3rd day of December, 1927.
